UNITED STATES PATENT OFFICE.

THEODORE WALLACE AND PERCY WALLACE, OF PETERSHAM, NEAR SYDNEY, NEW SOUTH WALES, AUSTRALIA.

HAMPER FOLDING GO-CART.

1,189,515.

Specification of Letters Patent.

Patented July 4, 1916.

Application filed March 5, 1914. Serial No. 822,619.

To all whom it may concern:

Be it known that we, THEODORE WALLACE and PERCY WALLACE, citizens of the Commonwealth of Australia, residing at 240 Parramatta road, Petersham, near Sydney, New South Wales, Australia, have invented a new and useful Hamper Folding Go-Cart, of which the following is a specification.

The object of this invention is the construction of a hamper folding go-cart which may be packed with articles, and if placed in a prone position with the wheels shielded and hidden, will have the appearance only of a hamper which may be conveniently stowed away as luggage without risk of injury to the mechanical parts by which it is made serviceable to act as a go-cart.

The mechanism provided is so arranged that the hamper may be wheeled instead of being carried by hand, as is the usual practice, and, when desired, may be restored to its hamper-like appearance, and be made to assume the prone position, the feature of the invention being that the parts utilized in the construction of the hamper are likewise serviceable for use as a go-cart.

Referring to the accompanying drawings, in which similar letters are used to indicate similar parts throughout the different views: Figure 1 is a side elevation, showing framework, wheels attached thereto, the connected parts for operating the wheels, and, collapsible canopy convertible into hamper cover as shown by dotted lines. Fig. 2 is an elevation of the opposite side to Fig. 1, showing duplicate parts as in Fig. 1, with shortened rod attached to trundling handle. The canopy and dotted cover are omitted, and the forward part of framework broken away. Fig. 3 is an elevation of the parts shown in Fig. 1, arranged in their collapsed positions to form a transportable hamper. Fig. 4 is a plan, showing the underside parts, such as bottom framing, tie bars, wheel axles, securing collars, wheels, crank connecting rods, and wheel guards. Fig. 5 is a plan of top side of Fig. 4, showing hamper compartment, cover and attachments, wheel guards, also trundling and actuating handle with jointed connections to back frame. Fig. 6 is an end elevation of framework, as seen from the rear position, with wheels and their guards, also crank support for canopy. Fig. 7 is a perspective detail view of fragments of the jointed parts of the handle connections, showing stop for-

mation. Fig. 8 is a perspective detail view, showing cranked end of trundling and actuating handle attached to fragment of back frame, and actuating rod located in guard bracket. Fig. 9 is a perspective fragmentary detail of actuating rod, bow shaped pivoted lever attached to frame and wheel connecting rod, showing also limitation stop. Fig. 10 is a perspective fragmentary detail of a wheel crank, showing method of placing securing collars and framework in position.

The drawings generally are intended to show the skeleton construction, divested of the covering material which may consist of wicker-work, compressed fiber molded into any suitable shape, or other materials suitable to obtain the hamper-like construction, and to form the wheel shields.

The under framing serves as the foundation part of the structure, and is made of two parts, each of which has its fore-and-aft side piece A, with the forward turned in ends A¹ secured to each other by the connecting bar A², and are fastened in their parallel position by the tie bars B, B¹. The rearward ends are secured to a rectangular shaped frame consisting of the transverse piece C and the vertical side pieces C¹ C², which are kept equi-distant by the bow shaped tie bar D which, besides being a stiffener, is serviceable for handling the hamper, and for steadyng the vehicle when operating the mechanical parts. To the transverse piece C the guard brackets E are secured. The fore-and-aft pieces A are pierced to receive the axles F, whose cranks F¹ form part of the axle.

To connect up the parts as shown arranged in Fig. 4, first the collars G are placed in position on the cranked part F¹ as shown in Fig. 10, and then moved along to the axle F and secured by the pins G¹. The frame parts A are then placed in position over the cranks and against the collars, and secured by the connecting and tie bars A², B, and B¹. The cranks are then in their correct position outside of the under framing, and are prevented from moving endwise by the respective collars G, and are linked together by the operating connecting rods H, which are necessarily kinked or set out of line inwardly as at H¹ so as to be attached to the bow shaped levers I by pivot pins J, pivot pins J¹ being provided for attaching the bow shaped levers I to the frame parts A. The fixed stops K in the parts A

are used to limit the range of movement of the bow shaped levers I. These levers are placed in different positions on the opposite sides of the framing, forwardly on the right hand, and rearwardly on the left hand, the object being to apply the power to the respective cranks in the most effective manner, and by keeping the pivotal pins J and J¹ in the same relatively parallel positions as the axles and their associated cranks, to obtain harmonious action without undue friction, the curving of the levers serving to assist in the accomplishment of this object by insuring a direct forward thrust being put upon connecting rods H, by which the wheels W and cranks are made to move simultaneously.

In Figs. 1 and 2, the stops K, located against the rear edge of the curved levers I, effectually prevent the wheels and their associated parts being disarranged while the hamper is being wheeled. Similarly, when the lever I is in its changed position, as in Fig. 3, the said stops K serve to prevent the disarrangement of the parts. To the ends of the extended parts I¹ of the said levers I, the long connecting rod L on the right hand side of the frame, and the short connecting rod L¹ on the left hand side of the frame, are attached by pivotal pins L² L³, and at their opposite ends by pivotal pins L⁴ L⁵ to the trundling and actuating handle M, which is pivoted by pins M¹ M² to the vertical side pieces C¹ C² of the rear frame.

In Fig. 8 the handle M is shown curved both upwardly and downwardly, to provide the necessary clearance for connecting the end part M³ to the connecting rod L¹, so that in reversing or changing the position of the handle M, as shown in Fig. 3, the connecting rods L L¹ will not chafe with the rear wheel cranks, and the bow shaped part of the said handle will have the necessary clearance to pass the tie bar D. To the upper ends of the side pieces C¹ C², jointed connecting bars, composed of pieces N N¹ joined together by the center pins O¹, are attached by the pins O, the parts N¹ being united to the handle by pins N², these parts being free to move on their respective pins. The parts N¹ are provided with stop pieces N³ which, when brought into contact with the contiguous edge of the part N, serves to convert the two parts into a rigid rod, and being set slightly out of the center, answers the purpose of a locking bar by which the handle M and the associated operative parts are rigidly secured.

In Figs. 1 and 2 the parts are shown locked in the open position, and in Figs. 3 and 5 they are locked in their closed position. The finger rings N⁴ are provided for the purpose of unlocking the parts N N¹. The downward movement shown in dotted lines in Figs. 1 and 2 produces a change in

the position of the handle M, which is shown in dotted lines—these indicate the direction in which the handle is to be moved upon the pins M¹ M², and when it is laid in its prone position as in Fig. 3, the jointed parts N N¹ occupy a reverse position to that shown in Fig. 1, the finger rings N⁴ standing upwardly instead of downwardly. An upward pull upon these rings will unlock the parts N N¹ and give the requisite freedom to allow of the handle M being again raised to its upward position as indicated in Figs. 1 and 2.

So far the invention has been described in its skeleton formation. To provide the receptacle for holding the articles, the floor part P is attached to the under framing A A¹ A² and the stays B B¹, and upon it are secured the ends Q Q¹ and the sides R, one of which is omitted from Figs. 1, 2, and 3, to give clearness to the other associated parts. The wheel guards S, which extend the full length of the hamper, also inclose the operating mechanical parts. These guards are secured to the end part Q by metal frames T (see Fig. 4), and are shown open ended for the purpose of inspecting the various connections. At the other end a rounded formation S¹ is adopted, and secured to the brackets E, one of which is placed on each side of the hamper.

Provision is made for covering in the hamper by means of collapsible lids U U, held together by hinges U¹. The connecting rods V, two of which are provided on each side of the hamper, are attached side by side at one end to the upstanding supports V¹, which are secured to the floor part P in a central position to permit of each half of the cover U occupying its right position, the cranked parts V² as clearly shown in Fig. 6 providing the requisite space to permit of the parts U U, when folded together, being laid either to the right or to the left, as in Fig. 5, so as to wholly uncover the hamper to give access for packing purposes, or to be arranged in the manner shown dotted in Fig. 1, by which each half of the cover will be placed in their proper position as shown in Fig. 3. To handle the cover conveniently, the finger loop U² is connected at the hinged part, and to retain the connecting rods V in any desired position the screw threaded bolts having wing nuts V³ are provided. The said cover is likewise serviceable for use as a canopy when the appliance is used as a go-cart. When placed in the elevated position at the back end of the go-cart, as shown in Fig. 1, by reversing its position it may be made similarly serviceable at the other end of the vehicle. Side screens or curtains X may be provided as an attachment to the lids U U.

In Figs. 1 and 2, the invention is shown in a trundling position, but in Figs. 3 and 6

the wheels W have been put out of action, and the apparatus is shown in its folded or collapsed position as a hamper.

The transposition of the parts from the open to the closed position is effected in the following manner: First, by moving the jointed connecting bars downward, which has the effect of forwardly tilting the handle M. The bow shaped tie bar D is grasped in one hand, and the actuating handle M in the other, the latter being carried forwardly over the vehicle. The connecting rods L L¹ are thus drawn backward and the bow shaped levers I are swung upon their pivots J¹ thereby raising the operating connecting rods H to which the cranks F¹ are attached upwardly, thus the wheels W are lifted clear of the ground and take up their position between the wheel guards S and the sides R (Fig. 6). The levers I, upon completing their movement, are brought against the stops K, Figs. 1 and 3, and at the same time the parts may be locked by a downward pressure being put upon the jointed connecting bars N N¹, the stop pieces N² limiting the range of movement. An upward pull upon the finger rings N⁴ will unlock the jointed connecting bars, and leave the handle M free to be operated in the reverse direction, and through the medium of the connecting rods and bow shaped levers to again bring the apparatus into the open or trundling position. The cover U U, when pressed downwardly, assumes a lozenge shape, as shown dotted in Fig. 1, each half automatically taking the prone position shown in Fig. 3. The back end of the body part may be made movable and inclined, to provide further room when in use as a go-cart.

Having now described our invention, what we claim as new and desire to secure by Letters Patent is:—

1. In a hamper folding go-cart, an under-frame comprising two parallel side pieces having bent ends, a bar connecting said ends and means for bracing said side pieces, in combination with a rear frame to which said under-frame is attached, a pair of cranked wheel axles mounted on said side pieces, operating rods connecting said axles on each side of the under-frame, and curved levers pivoted to said under-frame and attached at their operating ends to said axle-connecting rods, the curvature of said levers permitting them to act and fold to the best advantage in turning the cranked parts of said axles up and down, said levers being arranged to fold under said rods.

2. In a hamper folding go-cart, the operating connecting rods pierced at each end

to receive the wheel cranks, each kinked at a different part of its length inwardly in the direction of the side pieces of the under-frame, and pierced to receive pins by which attachment is made to a pair of bow shaped levers by which the said rods are operated, as described and shown, and for the purposes set forth.

3. In a hamper folding go-cart, the actuating and trundling handle made bow shaped and having the two side parts made with double crank formation, piercings in each of the end curved parts to receive pins by which attachment is made to the lower part of the vertical side pieces of a rear frame, and further pierced at a part of their length upwardly for attachment to jointed connecting rods by which they are attached also to the upper ends of the aforesaid rear frame, and pierced at both ends to receive pins by which attachment is made to long and short connecting rods, and, long and short connecting rods attached at one end to the aforesaid actuating handle, and at their other ends to bow shaped levers, as described and shown, and for the purposes set forth.

4. The body of a hamper folding go-cart, consisting of a floor part, front, back, and side parts attached to the said floor part, overhanging side parts attached to and dependent from the top side of the body part and secured at one end by frame pieces and at the other end to guard brackets also attached to the end framework of the said body part, the space formed between the said overhanging parts and the side parts serving as chambers to hold the wheels, their operating parts, and attachments, as described and shown, and for the purposes set forth.

5. In a hamper folding go-cart, the hamper lids, convertible into a canopy, comprising two parts, hinges securing said parts together to allow of opening and closing movements, a flexible loop attachment secured at the hinged parts, two connecting rods attached on both sides of the lids at the ends and united at their other ends to supporting standards, the said standards being attached to the body part, as described and shown, and for the purposes set forth.

In testimony whereof we have signed our names to this specification in the presence of two subscribing witnesses.
